FUSE

John B. MacLean, Peru, Ill., assignor to General Time Corporation, New York, N. Y., a corporation of Delaware

Application August 14, 1944, Serial No. 549,310

6 Claims. (Cl. 102—71)

1

This invention relates in general to fuzes and more particularly to time fuzes for rocket bombs or similar projectiles. The main object of the invention is to provide an improved fuze of this type having new and novel safety and other features.

According to one feature of the invention, the timing mechanism is released to start the timing operation as the rocket is fired from its firing tube.

Another feature of the invention relates to the means for normally maintaining the fuze in "safe" condition and for arming same only after the rocket leaves its tube and has ceased acceleration and begun deceleration.

According to a further feature of the invention, the acceleration of the rocket as it leaves the tube initiates the timing operation and subsequent deceleration of the rocket arms the fuze for detonation.

A further feature of the invention resides in the provision of means for preventing detonation of the fuze by the setback force on the firing pin as the rocket is fired or by air pressure on the nose of the fuze set up by a rocket fired from an adjacent tube and permitting detonation of the fuze upon impact or at the expiration of a predetermined time interval.

The above and other objects and features of the invention not specifically mentioned and a clear understanding of the construction and operation of the invention may be had from a perusal of the following specification when read in connection with the accompanying drawing comprising Figures 1 to 5, inclusive, in which

Fig. 1 is a cross-sectional view of the complete fuze with a portion of the head in elevation;

Fig. 2 is an end view of the fuze as seen from the right in Fig. 1 with the booster cup removed;

Fig. 3 is a side elevation of the inertia movement;

Fig. 4 is an end elevation of the inertia movement; and

Fig. 5 is a perspective view of the firing pin and the release mechanism therefor.

Fig. 6 is a detailed view in elevation of gears 69 and 71.

Fig. 7 is a detailed view in elevation of gear 59 and hub member 56.

Fig. 8 is an elevational view of plate 49 taken on the line 8—8 of Fig. 4.

In Fig. 1 the fuze is shown ready for attachment to a rocket. All movable parts are in a cocked position.

In Figs. 3 and 4 the inertia movement is shown with each movable part in the position assumed after the rocket has decelerated.

2

Referring to the drawing in detail the fuze casting consists essentially of a body portion 1 and a head portion 3. The body portion 1 is provided with a threaded section 2 to enable the fuze to be screwed into the body of the rocket bomb. The head section 3 includes a reduced projecting portion 4 which is adapted to fit into a center bore of the body 1. The head is maintained in the body by means of the spring wire 5 which fits into a groove in the body 1. The body 1 is also provided with a plurality of screws 6 the ends of which lie against the spring wire 5 and these screws 6 may be turned down in order to force the spring wire 5 part way into a complementary groove in the reduced portion 4 of the head 3. Thus the head 3 is maintained in the body 1 but may be easily rotated in order to set the time of operation of the fuze as will be described later.

A thumb screw 7 is also provided having its end bearing against the spring wire 5 and this thumb screw 7 may be tightened in order to fixedly attach the head 3 to body 1 after the time setting has been effected. The coil spring 8 surrounds the shank of screw 7 and tends to maintain the screw in its set position.

The body 1 is provided with a projecting flange portion 9 having several notches therein, this flanged portion being adapted to butt up against the end of the rocket bomb when the fuze is inserted therein and the notches being provided to enable the fuze to be screwed into the bomb with a suitable wrench.

A portion of the head 3 is knurled as at 10 so that the same may be more easily grasped to effect the time setting. The surface of the head 3 is also provided with the scale 11 which indicates the time of operation of the fuze.

Mounted within the body 1 is the timing device 26. This device is secured to the body by means of screws 33 and consists of a plurality of plates held together by screws (not shown), the timing movement being located within these plates. Since this timing movement forms no part of the present invention the same has not been shown in detail. It is sufficient for the purposes of this explanation to state that the movement terminates in a rotatable hub which mounts the timing disc 27, the hub and disc rotating at a predetermined rate depending upon the desired extent of the time of operation of the fuze.

Also mounted within a cavity at the right end of body 1 is an inertia movement located on the plate 41 which in turn is mounted on bosses 39 of the body by means of screws 40. The right hand end of the fuze body is closed by means of the plate 43 mounting the closure cup 45 and the

booster cup 44 which is screwed into the body at 45 and contains the explosive booster charge 86.

The head 3 is provided with a center bore through which extends the firing pin 13. The firing pin is provided at its left hand end as viewed in Fig. 1 with the striker 14 which is screwed to the end of firing pin and held in the proper position by bending over a portion of the inner hub of the striker against a slabbed portion of the firing pin as shown at 16. The striker 10 is provided with a cylindrical extension 15 which slides into the hole 20 formed in the cylindrical portion 12 of the head assembly. A further hole 15 21 is provided to accommodate the firing pin sleeve or cup 23 which retains one end of the firing pin spring 22, the other end of which bears against the shoulder formed at the left hand end of hole 21 as shown in Fig. 1.

The firing pin 13 is provided with an enlarged portion 24 and the firing pin spring cup 23 bears against this enlarged portion in order to bias the firing pin to the right as viewed in Fig. 1 and to force same to firing position when the cup is released as will be explained later.

The cup 23 is held in its left hand position with the spring 22 under compression by means of the cocking pin 25 having a slabbed portion in engagement with cup 23. Secured in the cocking pin 25 is the cocking pin screw 31 which extends from the right hand end of head assembly 3, the latter being provided with a slot for movement of the cocking pin screw to allow the cocking pin 25 to rotate and release the cup 23.

Mounted on the right hand surface of the hub 4 of the head assembly 3 is a firing lever 28 which is rotatably held to the head by means of screw 29 and is provided with a hook portion 30 adapted to engage the cocking pin screw 31. This firing lever is provided at its other end with a projection 32 which is engaged by the lateral projection 33 of the timing disc lever 34 which in turn is rotatably mounted to the head assembly by means of screw 35. The timing disc lever 34 terminates at its opposite end in the laterally extending projection 36 which is adapted to engage the periphery of the timing disc 27. The arrangement of the firing pin, cocking pin, timing disc and control levers is clearly disclosed in Fig. 5 of the drawing.

The timing disc 27 is provided with a notch 37 and the projection 36 of the lever 34 drops into this notch to release the firing pin after the pre-determined set time interval. Extending through the timing movement 26 and into the notch 37 is the arming pin 46. This arming pin normally holds the timing disc in its zero position with the time movement in energized condition and is moved to the right (as seen in Fig. 1) by means of the arming pin spring 47 in order to start the timing of the interval during which the detonation of the fuze is delayed.

Referring now more particularly to Figs. 3 and 4 of the drawing the inertia movement comprises parallel spaced plates 48 and 49 which are held in spaced relationship by means of the lateral plates 50 and 51. Plates 48 and 49 have extending projections which fit into notches in the mounting plate 41, the edges of these projections being bent over in order to securely hold the movement to the mounting plate. The inertia movement consists essentially of an escape wheel 69 which is rotatably mounted on a stub shaft 67 secured to plate 49. Riveted to the outer surface of this escape wheel is the inertia weight 70. Also secured to the escape wheel and rotatable therewith is the pinion 77. Mounted on a

second stub shaft 75 is the governor or pallet 74 which is provided with the two pallet pins 76 adapted to engage the teeth of the escape wheel 69. The pinion 77 is in engagement with the gear wheel 59 fixedly mounted on shaft 55 which has its bearings in the two plates 48 and 49. Fixed to the gear wheel 59 is the hub or cam member 56 which controls the release pin 60 to be described later. Also mounted on shaft 55 between the plates 48 and 49 is an assembly comprising a hub portion 52 and the two segment gears 53 and 54. This assembly is rotatably mounted on shaft 55 so that gear wheel 59 may be rotated without moving said assembly.

Extending from plate 49 is an arm or bracket 72 to which is secured one end of the coil spring 73. This spring 73 is coiled around the shaft 67 and the other end of the spring is in engagement with the inertia weight 70 as seen in Fig. 3. The split washer 68 engages a groove on the end of shaft 67 in order to retain the spring in position. Thus the escape wheel 69 is biased for clockwise rotation by means of the spring 73.

A cylindrical tube 65 extends between plates 50 and 51 and provides passage for the firing pin through the inertia movement device. The gear segments 53 and 54 extend through slots in plate 51 and the teeth of these segments engage rack teeth 79 provided on the detonator slider 42 as shown in Fig. 2 of the drawing. The toothed portion of gear segment 53 extends around approximately two-thirds of its periphery while the other portion of gear segment 54 (as shown in Figure 1) extends around approximately one-fourth of its periphery. The gear segments 53 and 54 are positioned on shaft 55 so that the teeth of both segments engage the rack teeth 79 to start movement of the detonator slider. When the slider has been moved a short distance the teeth of segment 54 are disengaged, but the teeth of segment 53 are still engaged and drive the slider to the end of its travel. The detonator slider 42 mounts the detonator 84 and is arranged to move between plates 48 and 49, carrying the detonator to a position in line with the firing pin. The release pin 60 extends through the two gear segments 53 and 54, through the semi-circular slot 66 in plate 49, and into engagement with the control hub or cam 56. The semi-circular slot 66 permits the pin 60 to be turned through approximately 180°. The release pin is biased to the left (as seen in Fig. 4) by means of a spring 61, one end of which bears against the segment gear 54 and the other end of which bears against a collar on the release pin.

As seen in Fig. 4 the control hub 56 has a notch 57 transverse of its peripheral edge, this notch or slot being directly in line with a hole in the gear 59. The control hub 56 is also provided with a further cutaway portion 58 which connects with the slot of notch 57 but does not extend all the way across the peripheral face of the hub.

In order to prepare the inertia movement for operation, the escape wheel 69 is rotated in a counter clockwise direction about a turn and a quarter which turns gear 59 about one-half turn until the hole 71 therein is in register with the hole in gear 59 and the release pin 60. A pointed instrument may then be inserted through these holes in the escape wheel 69 and gear 59 into engagement with the end of release pin 60 moving the release pin to the right as seen in Fig. 4 until it is in line with the cutaway portion 58. The escape wheel 69 may then be released and

will be rotated in a clockwise direction until stopped by the engagement of pin 60 with the wall surface of the cutaway portion 58 of control hub 56. In this position the release pin 60 extends through plate 48 and engages a hole in one end of an arming pin lever 81 as clearly shown in Figs. 1 and 2 of the drawings. This arming pin lever 81 is rotatably mounted on plate 48 by means of the screw 83. The other end of the arming pin lever is bent at an angle to form the projection 82 against which lies the end of the arming pin 46.

The plate 41 has a bracket 63 bent up at right angles thereto and this bracket mounts a hub 78 which is provided with internal screw threads. Gear 59 has a second hole therein which is adapted to be engaged by the end 89 of a lock pin 87 which is inserted through a hole in the wall of the body 1 and is provided with screw threads which screw into the hub 78. The outer end of the lock pin 87 is bent at an angle and provided with a hole 88 adapted to receive a wire so that the pin may be sealed in the fuze during transportation and before the fuze is ready for assembly in the rocket bomb. This lock pin is an additional safety feature to insure that there will be no inadvertent arming of the fuze during handling.

The left hand end of the head assembly 3 is provided with a thin metal cover 18 held in position by a rib which fits into a groove in the head as shown at 19. A striker retainer plate 17 is provided which rests on the end of the head section 3 and against which bears the striker 14. This striker retainer is provided so that the firing pin will not be moved to firing position by the set-back force as the rocket bomb leaves the firing tube. The striker cover 18 is provided to prevent the air pressure from firing the fuze when a rocket bomb is fired from an adjacent tube.

Referring now to the operation and use of the fuze as described in this application, when it is desired to mount the fuze in a rocket bomb the lock pin 87 is removed and the fuze is secured into the bomb as previously explained. The thumb screw 7 is then loosened and the head 3 is turned until the desired firing time interval is indicated on the scale 11. The thumb screw 7 is then tightened so that the head 3 and body 1 will be securely held together. This fuze is mounted on the nose of the rocket bomb and as the bomb is fired the fuze moves in a direction to the left as seen in Fig. 1. The inertia movement is so mounted within the fuze body that as the bomb leaves the firing tube the inertia movement travels in a direction toward the bottom of the sheet as it is positioned in Fig. 3. The terrific acceleration of the bomb and fuze causes the inertia weight 70 to rotate the escape wheel 69 in a counter clockwise direction. This rotation of the escape wheel and the corresponding rotation of gear 59 in a clockwise direction moves the control hub 56 so that the release pin 60 leaves the cutaway portion 58 and enters the notch 57. Since the release pin 60 is now free to move to the left as shown in Fig. 4 it is moved in this direction by means of the springs 61, thereby withdrawing the end of the release pin from the hole in the arming pin lever 81.

Referring to Fig. 1, when the arming lever pin 81 is freed by the release pin 60 the arming pin 46 moves to the right under power of the spring 47 thereby withdrawing the left hand end of the arming pin from the notch in the timing disc 37. This initiates the operation of

the timing device and the timing disc 27 is rotated as indicated by the arrow in Fig. 5. As long as the bomb is accelerated or maintaining its speed the set-back force on the inertia weight 70 overcomes the power of spring 73 and the weight will maintain the inertia movement in the position in which the release pin has been released. As soon as the bomb starts to decelerate and the power of spring 73 is greater than the set-back force on the inertia weight 70, the spring rotates the escape wheel in a clockwise direction which through pinion 17 rotates gear wheel 59 and shaft 55 in a counter clockwise direction. Rotation of shaft 55 also rotates the segment gears 53 and 54 which are in engagement with the rack teeth 79 on the detonator slider 42. Thus the slider 42 is moved to armed position by the inertia movement and carries the detonator 84 into the path of the firing pin 13 and in line with the closure cup 85. At an expiration of the set time interval the projection 36 of the timing disc lever 34 drops into the notch 37 of the timing disc 27. Projection 33 thereby releases projection 32 of the firing lever 28 which in turn rotates so that the hook 30 releases the cocking pin screw 31. This frees the cocking pin 25 so that it can rotate and allow the firing pin spring cup 23 to pass the slotted portion of the cocking pin 25. Thus the firing pin is moved to the right by the spring 22 detonating the fuze which in turn brings about the firing of the bomb. The power of spring 22 is sufficient to move the firing pin to the right as viewed in Fig. 1 even though the retainer plate 17 is still in place. As previously stated the plate 17 is made of very thin metal and buckles under the power exerted by the firing pin spring 22.

In case the rocket should strike some object before the expiration of the set time interval, the striker cover collapses driving the striker and firing pin through the striker retainer and detonating the fuze.

From the foregoing it will be seen that the timing interval of the fuze is initiated just as the rocket bomb leaves its firing tube. The fuze is maintained in safety condition until the bomb begins to decelerate at which time the fuze is armed. Means are provided to prevent the setback on the striker and firing pin from detonating the fuze and further means are provided to prevent air pressure which may be exerted upon the end of the fuze when a rocket is fired from an adjacent tube from operating the firing pin to detonate the fuze.

These and the other features of the invention might be incorporated in various forms or modifications of the construction shown herein, but such modifications are intended to be covered by the present invention.

What is thought to be new and is desired to have protected by Letters Patent is set forth in the appended claims.

What is claimed is:

1. In a fuze for a rocket bomb, the combination of a firing pin normally tensioned toward a detonator, a normally energized timing device, a cam disc controlled thereby, means controlled by said cam disc for effecting release of said firing pin, an arming pin normally blocking said cam disc, and an inertia device movable by the acceleration of said bomb as it is fired from its tube for controlling the removal of said arming pin from blocking position to initiate the operation of said timing device.
2. In a fuze for a rocket bomb, the combination

of a firing pin normally tensioned toward firing position, a timing device for releasing said firing pin, a detonator slider normally held in safe position, and a device including a spring biased inertia member movable in one direction against said bias by the acceleration of the bomb to control the initiation of the operation of said timing device and a spring biasing said member for movement in the opposite direction upon deceleration of the bomb to move said detonator slider to armed position.

3. In a fuze for a rocket bomb, the combination of a firing pin normally tensioned toward firing position, a spring driven timing device, a cam disc controlled thereby, means controlled by said cam disc for effecting release of said firing pin, an arming pin normally blocking said cam disc, a detonator slider normally held in safe position and a device including a spring biased inertia member movable in one direction by the acceleration of the bomb for controlling the removal of said arming pin from blocking position to initiate the operation of said timing device and a spring biasing said member for movement in the opposite direction upon deceleration of the bomb to move said detonator slider to armed position.

4. In a fuse for a rocket bomb, the combination of a firing pin normally tensioned toward firing position, detonator carrying means normally held in safe position, a timing mechanism including a rotatable member for controlling release of said firing pin, means blocking the rotation of said member, spring biased inertia means movable against said bias by acceleration of the rocket as it is propelled from its firing tube for controlling the withdrawal of said blocking means to initiate the operation of said timing mechanism, and means controlled by the movement of said inertia means under the influence of the spring bias upon deceleration of the rocket for moving 40 said detonator carrying means to armed position.

5. In a fuze for a rocket bomb, the combination of a firing pin normally tensioned toward firing position, a time movement for controlling release thereof, a detonator slider normally held in safe position, a spring biased inertia member, means actuated by movement of said member against the spring bias by acceleration of the rocket to start said time movement and means actuated by movement of said member in the opposite direction for thereafter moving said detonator slider to armed position.
6. In a fuze for a rocket bomb, the combination of a firing pin normally tensioned toward firing position, a detonator and carrying means therefor normally held in safe position with said detonator out of the path of movement of said firing pin, a spring biased inertia member movable in one direction against the spring bias by the acceleration of the rocket as it is propelled from its firing tube and movable in the opposite direction by the spring upon subsequent deceleration of said rocket, means controlled by the movement of said inertia member by acceleration for releasing said firing pin and means actuated by the movement of said inertia member upon deceleration for moving said detonator carrying means to armed position.
